UNITED STATES PATENT OFFICE

WINTHROP T. SCARRITT, OF UTICA, NEW YORK

MACHINE FOR MANUFACTURING STIFF SPIRAL TUBES

Application filed May 1, 1931. Serial No. 534,407.

An object of the invention is to provide a machine for manufacturing tubes, which may be operated rapidly to manufacture stiff tubes by bending a strip of stock spirally and interlocking the sides of adjacent helixes.

Another object of the invention is to provide rolls for bending the sides of the strip of stock into positions to permit the sides of the strip to readily interlock. Preferably the stock is bent by the rolls with one side bent in one direction and the opposite side bent in an opposite direction, and additional rolls then engage the stock to bend the sides to form acute angles relatively to the body of the stock, the additional rolls also serving to tilt the body of the stock transversely at an angle to the spindle on which the body is to be wound.

Still another object of the invention is to lead the stock to the spindle on which the stock is wound at approximately right angles to the axis of the spindle and at an acute angle relatively to the longitudinally extending outer surface of the spindle, there being means at the spindle for directing the strip of stock spirally around the spindle.

A further object of the invention is to provide a finger for tucking the interlocking edges of the strip of stock into close association and to provide a roll for compressing the said interlocking edges. Preferably means are provided for leading a thread of solder between the interlocking sides of the helixes formed by the stock before they are compressed and there are also means to heat the interlocked sides of the helixes to make, with the solder, a tight joint at the said interlocking sides.

The invention furthermore comprehends means for adjusting the parts of the machine to adapt them to meet varying conditions and different sizes of stock.

Additional objects of the invention will appear in the following specification in which the preferred form of the invention is described.

In the drawings similar reference characters refer to similar parts in all the views, of which

Figure 1 is a plan view of the machine, Figure 2 is a side elevation of the machine, Figure 3 is an enlarged sectional view illustrating the spindle and its mountings and showing the spirally-disposed guide, 55

Figure 4 is an enlarged view illustrating the rolls for bending the sides of the strip of stock,

Figure 5 is a view on the line 5—5 of 60 Figure 4,

Figure 6 is a sectional view on the line 6—6 of Figure 4,

Figure 7 is a sectional view on the line 7—7 of Figure 4,

Figure 8 is a fragmentary sectional view 65 illustrating the finger which serves to tuck the interlocking sides together,

Figure 9 is a fragmentary sectional view illustrating the manner in which the roll 70 serves to compress the interlocking edges of the helixes, and

Figure 10 is a view illustrating a stiff spiral tube manufactured by the machine.

By referring to the drawings it will be seen that a base 11 is mounted on legs 12 and that there are bearings 13 in which a shaft 14 is journaled, there being also bearings 15 and 16 in which a shaft 17 is journaled. There is a sprocket wheel 18 on the shaft 14 and there is a sprocket wheel 19 on the shaft 17, these sprocket wheels 18 and 19 being connected by a sprocket chain 20. There are preferably two pulleys 21 and 22 on the shaft 14, one of the said pulleys being fixed to the shaft and the other pulley being loose thereon.

The outer end 23 of the shaft 17 is tapered, as will be seen by referring to Figure 3 of the drawings, and mounted on this tapered end 23 of the shaft 17 there is a sleeve or spindle 24, which has an aperture 25 through which a screw 26 is disposed, the screw meshing in a threaded opening 27 in the tapered end 23 of the shaft 17. It will be understood 90 that with this construction the sleeve or spindle 24 may be readily removed and may be replaced with another spindle of the same or of a different diameter. At the outer side of the bearing 16 there is disposed 95 100

a collar 28 which is held in place by means of screws 29, which are disposed through openings in the collar 28 and which mesh in threaded openings in the bearing 16. 5 Around this collar 28 there is disposed a guide member 30 which may be readily replaced with a guide member of a different size when a different size or type of sleeve or spindle 24 is used. The guide member 30 has an opening 31 through which the sleeve or spindle 24 is disposed and the guide member 30 is held in place on the collar 28 at the bearing 16 by means of screws 32, which are disposed in openings in the guide 30 and 10 which mesh in threaded openings in the bearing 16. The said guide member 30 has a spiral surface 33 which serves to direct a strip of stock spirally around the sleeve or spindle 24.

15 Standards 34 are secured to the base 11 and secured to these standards 34 there is a frame 35 having bearings 36 and 37, a shaft 38 being journaled in the bearings 36 and a shaft 39 being journaled in the bearings 37. 20 The bearings 37 are in portions 35^a of the frame 35 which are detachable from the body of the frame 35 and are held in place by screws 35^b. This makes it possible to remove the portions 35^a of the frame for purposes 25 of adjustment. These shafts 38 and 39 are connected by gearing 40. Secured to the shaft 38 there is a roll 41 having a surface for engaging the middle portion of a strip of stock 42, the roll 41 having at one side an 30 end 43 of greater diameter than the portion 41 of the roll and the roll having at its other side an end 44 which is of less diameter than the portion 41. Secured to the shaft 39 there is a roll having a portion 45 for engaging the 35 middle portion of the strip of stock 42, with a portion 46 opposite the portion 43 on the first mentioned roll, the portion 46 being of less diameter than the portion 45, and there being a portion 47 of the other side of the 40 shaft 39 which is of greater diameter than the portion 45 and which is opposite the portion 44 of the first-mentioned roll.

45 It will therefore be seen that, as the strip of stock 42 passes between the two rolls, it will have one side 48 bent in one direction and its other side 49 bent in the opposite direction. The roll mounted on the shaft 38 has a portion 50 on the outer side of the portion 47 on the roll mounted on the shaft 39, 50 and the roll mounted on the shaft 39 has a portion 51 at the outer side of the portion 43 of the roll mounted on the shaft 38, the said portions 50 and 51 serving to hold the rolls 55 on the shafts 38 and 39 at all times in position relatively to each other. The roll mounted on the shaft 38 has a collar 52 between its portion 43 and one of its bearings, and there is also a collar 53 on the roll 60 mounted on the shaft 38 which is disposed 65

between the portion 50 of the roll and its other bearing.

It will, therefore, be seen that the lateral movement of the roll mounted on the shaft 38 will be prevented by the collars 52 and 70 53, and that the roll mounted on the shaft 39 will be prevented from lateral movement relatively to the roll mounted on the shaft 38 by the portion 50 on the roll mounted on the shaft 38, and the portion 51 mounted on the shaft 39. 75

The strip of stock 42, after it has been bent, as shown at 48 and 49, passes between the rolls 54 and 55, which are mounted to rotate on vertical axes, that is, at right angles to the axes of the shafts 38 and 39. The roll 54 has at one end an inclined portion 56 for bending the side 49 of the strip of stock at an acute angle relatively to the middle portion of the strip of stock, the 80 other end of the roll 54 having a portion 57 for bending the other side 48 of the strip of stock in an opposite direction and at an acute angle relatively to the middle portion 85 of the strip of stock, the central portion 58 of the roll 54 serving to tilt the middle portion of the strip of stock transversely, as illustrated in Figure 7 of the drawings. The companion roll 55 has surfaces which assist in shaping the strip of stock in the manner stated and as illustrated in Figure 7 of the drawings. The rolls 54 and 55 are mounted on vertically extending shafts or spindles 59 which have their outer ends disposed through sleeves 60 and which extend beyond the sleeves 60 and engage the blocks 61, the lower ends of the spindles 59 having shoulders at 62 which engage the upper sides of blocks 63, the shafts or spindles 59 extending through openings in the blocks 63 and having threaded lower ends which are engaged by nuts 64 which serve to clamp the spindles or shafts 59 to the said blocks 63. 100

One of the blocks 63 is engaged by a screw 65 which meshes in a threaded opening 66 in the frame 35 and with which meshes a nut 67 which presses against the frame 35 for locking purposes. There are also preferably threaded orifices 68 in the top of the frame 35 in which mesh screws 69 for pressing downwardly against blocks 61, which serves to press against the spindles or shafts 59 and to hold the parts in associated position. 105

As will be seen by referring to Figure 1 of the drawings, the strip of stock 42, after it has been bent in the form illustrated in Figure 7 of the drawings, and has been disposed as shown in the said figure, is led to the sleeve or spindle 24, one side of the strip of stock engaging the side of the spiral guide 33, as illustrated in Figure 8, and with the strip of stock tilted, so that its side 49 will be disposed in position for interlocking with the side 48 of a helix which has been formed on the sleeve or spindle 24. However, it will 110 115 120 125 130

be understood that the tilting of the strip of stock 42, as shown in Figures 7 and 8, also assists in the spiral movement of the strip of stock around the sleeve or spindle 24.

5 As the side 49 of the strip of stock 42 engages the side 48 of the strip of stock, which has been formed into a helix, a finger 70 serves to tuck the side 49 of the strip of stock into the side 48 of the strip of stock 10 which has been formed into the helix.

The said finger 70 is disposed through a guideway 71 in a member 72 which projects from a block 73 slidably mounted in a guideway 74. The finger 70 is adjustable longitudinally in the said guideway 71 and may be held in the said guideway in adjusted position by the screw 70^a which meshes in a threaded orifice in the member 72.

As stated, the block 73 is slidable in a 20 guideway 74, the said guideway 74 being pivoted on a vertical pin 75 mounted on the base 11 so that the block 73 may not only be moved inwardly or outwardly relatively to the spindle 24, but may be rotated with reference to the spindle 24 having in mind the width of the stock which is being used and other adjustments. The guideways 74 may be held in adjusted position by any suitable means, such as the screw 74^a meshing in a

25 threaded orifice in the guideway 74 and extending through a slot 74^b in the base 11, the head of the screw 74^a engaging the bottom of the face 11. Journaled in a bearing 76 in the block 73 there is a shaft having a roll 77, the roll 77 being best illustrated in Figure 9 of the drawings. This roll 77 has side portions 78 for engaging the strip of stock at the sides of the interlocked portions, the periphery of the roll 77 between its side

30 portions being curved transversely at 79 to press the interlocked sides of the strip of stock into close relationship. The shaft on which the roll 77 is mounted, has secured thereto a gear 80 which meshes with a gear 75 secured to a shaft 82 on which is mounted a sprocket wheel 83, the sprocket wheel 83 being connected by a sprocket chain 83^a with a sprocket wheel 84 secured to a shaft 85 journaled in the frame, the shaft 85 also

40 having secured thereto a sprocket wheel 86 which is connected by a sprocket chain 87 with a sprocket wheel 88 secured to the shaft 14.

It will be understood that by this means 55 the roll 77 will be rotated, the sprocket chain 83^a having sufficient play relatively to the sprocket wheels 83 and 84 to permit of the adjustment of the guideway 74 and the block 73 as desired. Journaled to the block 73 60 there is a threaded stud 89 which meshes in a threaded opening 90 in a locking member 91, the locking member 91 having collars disposed at the outer sides of a bearing 92 secured to the guideways 74, so that when the 65 threaded stud 89 has been moved for adjust-

ment, the locking member 91 may be turned to assist in holding the block 73 in adjusted position.

It will be understood from the above that as the strip of stock 42 is fed to the sleeve or spindle 24, as illustrated in Figure 8 of the drawings, and as the edge 49 of the strip of stock engages the edge 48 of a helix previously formed by the strip of stock, the finger 70 will press the edge 49 against the edge 48, when the roll 77 will serve to press the said edges 48 and 49 together, as illustrated in Figures 9 and 10, the inner sides of the helixes having the same diameter throughout, inasmuch as they are pressed in the manner set forth against the sleeve or spindle 24. Preferably the interlocked edges 48 and 49 are soldered together, there being a strip of solder 93 which is fed from a reel 94 over rolls 95 to a position between the said edges 48 and 49 of the said strip of stock, the said strip of solder being disposed between the edges before they are engaged by the finger 70, so that the finger not only serves to press the edge 49 of the strip of stock against the edge 48, but it also serves to bring the side 49 against the strip of solder 93, the roll 77 pressing the strip of solder 93 between the interlocking edges 48 and 49, and there being a torch 96 which serves subsequently to 90 heat the interlocking edges 48 and 49 to melt the solder and to make a tight joint. The strip of solder 93 is fed to the side 48 of the strip of stock which has been formed into a helix where it is engaged by the side 49 of the strip of stock which is about to form an adjacent helix, the finger 70 serving to press the said side 49 in the direction of the side 48 with the strips of solder therebetween. The strip of solder 93 is pulled from the reel 105 94 as the spindle 24 rotates.

What is claimed is:

1. In a machine for manufacturing stiff spiral tubes, a spindle, means for bending the sides of a strip of stock, means for feeding the strip of stock to the spindle to form helixes therearound, a finger disposed at the spindle for engaging the outer face of a bent side of the strip of stock for tucking the said bent side into a bent side of a helix for interlocking the said sides, and means for compressing the said bent interlocking sides. 110

2. In a machine for manufacturing stiff spiral tubes, a spindle, means for bending the sides of a strip of stock, means for feeding the strip of stock to the spindle to form helixes therearound, a finger disposed at the spindle for engaging the outer face of a bent side of the strip of stock for tucking the said bent side into a bent side of a helix for interlocking the said sides, and a roll having its periphery concave transversely for engaging the said interlocking sides for compressing the latter. 115

3. In a machine for manufacturing stiff 120

125

130

- 5 spiral tubes, a spindle, means for bending the sides of a strip of stock, means for feeding a strip of stock to the spindle approximately at right angles to the axis of the spindle and with the strip of stock tilted transversely to the outer surface of the spindle, means at the spindle for directing the strip of stock spirally around the spindle to form helixes, a finger for engaging a bent side of 70
- 10 the strip of stock for tucking the said bent side into a bent side of a helix for interlocking the said sides, and a roll having its periphery concave transversely for engaging the said interlocking sides. 75
- 15 4. In a machine for manufacturing stiff spiral tubes, a spindle, rolls for bending one side of a strip of stock in one direction and the other side of the strip of stock in the opposite direction, additional rolls for rotating on axes at an angle to the axes of the first 80 mentioned rolls for shaping the strip of stock with its body tilted transversely relatively to the axis of the spindle and with its sides bent outwardly at acute angles relatively to 85
- 20 the body of the strip, means at the spindle for directing the strip of stock tilted transversely relatively to the axis of the spindle spirally around the spindle to form helixes, and means at the spindle for interlocking the 90
- 25 bent sides of the helixes. 95
- 30 5. In a machine for manufacturing stiff spiral tubes, a spindle, rolls for bending one side of a strip of stock in one direction and the other side of the strip of stock in the opposite direction, additional rolls for rotating on axes at an angle to the axes of the first 100 mentioned rolls for shaping the strip of stock with its body tilted transversely relatively to the axis of the spindle and with its sides bent outwardly at acute angles relatively to the body of the strip, means at the spindle for directing the strip of stock spirally around the spindle to form helixes with the bent sides positioned for interlocking, and 105
- 35 a finger for tucking a bent side of the stock into the bent side of a helix formed on the spindle. 110
- 40 6. In a machine for manufacturing stiff spiral tubes, a spindle, means for interlocking sides of a strip of stock wound spirally on the spindle, a pivoted guideway, a block movable in the guideway and having a bearing, and a roll having a shaft rotatable in the bearing for pressing against the interlocked 115
- 45 sides of the strip of stock wound spirally on the spindle. 120
- 50 7. In a machine for manufacturing stiff spiral tubes, a spindle, a pivoted guideway, a block movable in the guideway and having a bearing, a roll having a shaft rotatable in the bearing for pressing against two sides of a strip of stock wound spirally on the spindle, and a finger carried by the block for tucking one of the sides into the other side prior to the action of the roll on the said sides. 125
- 55 8. In a machine for manufacturing stiff spiral tubes, a spindle, means for interlocking sides of a strip of stock wound spirally on the spindle, a pivoted guideway, a block movable in the guideway and having a bearing, a roll having a shaft rotatable in the bearing, the roll having a periphery concave transversely for pressing against the interlocked sides of the strip of stock wound spirally on the spindle. 70
- 60 9. In a machine for manufacturing stiff spiral tubes, a spirally disposed guide, a shaft disposed for rotating within the spirally disposed guide, and means at the shaft for pressing together laterally edges of a strip of stock which has been directed spirally around the shaft by the said guide to interlock the said edges. 80
- 65 10. In a machine for manufacturing stiff spiral tubes, a spirally disposed guide, a shaft disposed for rotating within the spirally disposed guide, means at the shaft for pressing together edges of the strip of stock which has been directed spirally around the shaft by the said guide, and a finger disposed in advance of the said means for engaging one edge to tuck the said edge into the other edge to assist in interlocking the 90
- 70 said edges. 95
- 75 11. In a machine for manufacturing stiff spiral tubes, a spirally disposed guide, a shaft disposed for rotating within the spirally disposed guide, a finger for engaging a bent edge of a strip of stock for tucking the said edge into another edge of the said strip of stock for interlocking the said edges, and a roll for engaging the interlocked edges for pressing them together. 100
- 80 12. In a machine for manufacturing stiff spiral tubes, a spindle, rolls for bending one side of a strip of stock in one direction and the other side of the strip of stock in the other direction, additional rolls for rotating on axes at an angle to the axes of the first 105 mentioned rolls for shaping the strip of stock with its body tilted transversely relatively to the axis of the spindle and with its sides bent outwardly at acute angles relatively to the body of the strip and a finger for tucking a bent side of the stock into the bent side of a helix formed by the stock on the spindle. 110
- 85 13. In a machine for manufacturing stiff spiral tubes, a spindle, means for bending the sides of a strip of stock, means for feeding the strip of stock to the spindle to form helixes therearound, and a finger disposed adjacent a formed helix positioned for engaging the outer face of a bent side of the strip of stock for tucking the said bent side into a bent side of the said helix for interlocking the said sides. 115
- 90 14. In a machine for manufacturing stiff spiral tubes, a spindle, means for bending the sides of a strip of stock, means for feed- 120
- 95 15. In a machine for manufacturing stiff spiral tubes, a spindle, means for bending the sides of a strip of stock, means for feed- 125
- 100 16. In a machine for manufacturing stiff spiral tubes, a spindle, means for bending the sides of a strip of stock, means for feed- 130

ing the strip of stock to the spindle to form helixes therearound, and a finger extending longitudinally of the spindle for engaging a bent side of the strip of stock for tucking the said bent side into a bent side of a helix for interlocking the said sides.

15. In a machine for manufacturing stiff spiral tubes, a spindle, means for bending the sides of a strip of stock, means for feeding the strip of stock to the spindle approximately at right angles to the axis of the spindle, means at the spindle for directing the strip of stock spirally around the spindle to form helixes, a finger at the spindle spaced from the third mentioned means and normally disposed beyond a bent side of the strip of stock disposed between the third mentioned means and the finger, the finger engaging the outer face of the said side of the strip of

20

stock to press the said side in the direction of the third mentioned means to tuck the said bent side into a side of a helix for interlocking the said sides, and a roll having its periphery concave transversely for engaging the said interlocking sides.

16. In a machine for manufacturing stiff spiral tubes, a spindle, a guide disposed at the spindle and having a cam face extending from the spindle, means for directing a strip of stock approximately at right angles to the axis of the spindle and tilted transversely to the longitudinally extending outer surface of the spindle, with one side of the strip disposed in close proximity to the outer surface of the spindle and with the other side of the strip spaced from the spindle and disposed against the cam face.
